UNITED STATES PATENT OFFICE.

ROBERT C. DOERR, OF CHICAGO, ILLINOIS.

RAILWAY-TIE.

No. 823,208.

Specification of Letters Patent.

Patented June 12, 1906.

Application filed February 10, 1906. Serial No. 300,446.

To all whom it may concern:

Be it known that I, ROBERT C. DOERR, a citizen of the United States, and a resident of Chicago, in the county of Cook and State 5 of Illinois, have invented certain new and useful Improvements in Railway-Ties; and I do hereby declare that the following is a full, clear, and exact description thereof, reference being had to the accompanying drawings, and to the letters of reference marked thereon, which form a part of this specification.

This invention relates to improvements in composite railway-ties composed of a material which is molded or formed while in a plastic state and afterward hardened and a metallic core embedded in said material.

The invention relates more specifically to rail-fastening devices carried by the tie, such 15 as fastening devices comprising rods which are partially embedded and anchored in the tie-body in the manner hereinafter described and which extend outwardly from the upper side thereof on both sides of the rail-line of 25 the tie in position to engage the base-flanges of the rail.

In another aspect the invention consists in forming said attaching-rods as integral parts of rods which constitute the core of the 30 composite tie.

The invention consists in matters herein-after set forth, and more particularly pointed out in the appended claims.

In the drawings, Figure 1 is a longitudinal 35 section, taken in two planes, of a railway-tie made in accordance with my invention and showing the manner of engaging the rails by the attaching-rods. Fig. 2 is a plan view thereof, partially broken away. Figs. 3 and 40 4 are cross-sections taken on lines 3-3 and 4-4, respectively, of Fig. 1. Fig. 5 is a fragmentary longitudinal section of the tie, showing a form of the invention different from that shown in the other figures.

As shown in the drawings, A designates 45 the body of the tie formed of cement or like moldable material having the characteristics hereinbefore set forth, and B B designate a plurality of rods extending longitudinally 50 through and embedded in the tie-body. Said rods constitute the core of the tie to give rigidity thereto.

C C designate rails attached to and supported on the tie, and D D designate tie- 55 plates which may be interposed between the tie and the rails.

b b' designate rail-attaching rods, which are anchored in the tie-body and extend upwardly therefrom for engagement with the base-flanges of the rails. Before the tie is 60 put into use the extended ends of said rods are straight and are disposed at right angles to the upper face of the tie, as indicated in dotted lines in Figs. 1 and 5. They are arranged in coöperating pairs at each end of 65 the tie, two of such pairs at each end of the tie being herein shown. The rods of each pair are spaced a distance apart to receive between the same the base-flange of the rail, and the rails are fastened to the tie by bending the upper ends of the rods inwardly over the base-flanges to constitute hooks b², b³. When the tie-plates D are employed, they are apertured and the rail-attaching rods extend therethrough, as clearly shown in Figs. 70 1 and 4.

In the construction shown in Figs. 1 to 4, inclusive, the rail-attaching rods b b' are formed integral parts of the core-rods B B, the said core-rods being turned upwardly at 80 their ends to form the attaching-rods. Each of the rods is turned upwardly at one end to constitute one of the rail-attaching rods, while the other end of the rod is made plain and extends from its upturned portion approximately to the opposite end of the tie. Two pairs of rail-attaching rods are provided for each rail, so that in the arrangement referred to there are provided eight core-rods, the disposition or arrangement of which is 85 indicated in Figs. 3 and 4.

In Fig. 5 I have shown a construction wherein the rail-attaching rods b⁴ and b⁵ are anchored in the body of the tie, but are made separate from the core-rods E thereof. The 90 said rods are turned inwardly at their upper ends over the base-flanges of the rail to constitute hooks b⁶ b⁷ in the manner before described. The means for anchoring the rail-attaching rods consists in providing the said rods with horizontally-turned inner end portions b⁸ b⁹. In this form of construction the core-rods may be made plain at both ends, or the core may be otherwise constructed.

I claim as my invention—

1. The combination with a molded railway-tie, of rail-attaching rods embedded therein and extending upwardly therefrom for engagement with the base-flange of the rail, the inner ends of said rods being bent 100 horizontally and constituting anchors therefor.

2. A molded railway-tie provided with longitudinally-arranged core-rods, the ends of which are bent upwardly and extend from the tie to constitute rail-fastening rods.
5. 3. The combination with a molded railway-tie, of rail-attaching rods embedded therein and extending upwardly therefrom for engagement with the base-flange of the rail, a tie-plate adapted to be interposed between the tie and rail, and provided with apertures through which said rail-fastening

rods extend, the inner ends of said rods being bent horizontally and constituting anchors therefor.

In testimony that I claim the foregoing as my invention I affix my signature, in presence of two witnesses, this 6th day of February, A. D. 1906.

ROBERT C. DOERR.
